KARL EGGART, OF ARBON, SWITZERLAND, ASSIGNOR TO FIRMA ADOLPH SAURER, OF ARBON, SWITZERLAND.

MACHINE FOR PUNCHING JACQUARD-CARDS.

1,118,481.

Specification of Letters Patent.

Patented Nov. 24, 1914.

Application filed February 3, 1914. Serial No. 816,147.

To all whom it may concern:

Be it known that I, KARL EGGART, a citizen of the Republic of Switzerland, residing at Arbon, Switzerland, have invented 5 certain new and useful Improvements in Machines for Punching Jacquard-Cards, of which the following is a specification, reference being had to the accompanying drawings, forming a part hereof.

10 This invention relates particularly to machines for punching cards for use in jacquard or automatic embroidering machines and more especially to machines of this character of the two-cycle type in which the 15 selecting devices for the punches which form the holes for the control of the movements of the fabric frame are arranged in two sets, one set of such devices operating in one phase while the other set is operating in 20 another phase so that the speed of production of the machine is practically doubled as compared with a machine of the previous type, and in which provision must be made for the punching of holes to control the separate 25 functions of the embroidering machine, such as festooning, perforating, etc.

In machines of the type particularly referred to the selecting devices for the special function punches are controlled manually by the operator and do not operate at every punching operation of the rest of the machine, but only when determined by the operator. The special function devices therefore do not operate in a double cycle. 35 Moreover, in a two-cycle machine the action of the operator which determines the selection of punches for a given stitch is not followed immediately by the punching for that stitch, but such punching takes place when 40 the operator performs the action necessary for determining the selection of the punches for the next stitch. On the other hand, the action of the operator in determining the selection of special function punches is followed 45 immediately by the punching and in the same phase of the machine. The action of the operator in determining the selection of the special function punches is indicated to him by the mark on the pattern which indicates 50 the stitch with which the special function is to commence and the operator therefore takes, in the same phase of the machine, the action which determines the selection of the stitch selecting punches and 55 the action which determines the selection of

the special function punches. Accordingly, because the operation of the special function punches takes place in what may be called the current phase of the operation of the machine, while the operation of the stitch 60 selecting punches, although initiated at the same time, takes place in the next succeeding phase of the machine, the special function perforations in the jacquard card would be formed in advance of the formation of 65 the stitch determining holes which should be formed on the same line in the card.

The principal object of the present invention is therefore to provide for such a construction of the machine as to insure the 70 formation of the special function controlling holes in such relative position in the jacquard card as to initiate the desired special function at the proper time and not too early.

75 Other features of improvement of the machine will also be referred to hereinafter.

In the drawings in which the invention is illustrated, Figure 1 is a view of a portion of a jacquard card punched by the machine. Fig. 2 is a view in front elevation of a punching machine in which the invention may be embodied. Fig. 3 is a top view of the punching mechanism by itself, partly broken away to save space and to show the 80 construction more clearly and on a much larger scale than that of Fig. 2. Fig. 4 is a detail view in section on the plane indicated by the line A—B of Fig. 3. Fig. 5 is a detail view in section on the plane indicated by the line B—C of Fig. 3. Fig. 6 is a detail view in section on the plane indicated by the line D—E of Fig. 3, but on a 85 still larger scale. Fig. 7 is a detail view in section on the plane indicated by the line 90 F—G of Fig. 6.

In the machine shown in the drawings, the usual pattern board 1 is represented as supported by a suitable frame and in front of the pattern board is mounted in the usual 100 manner the pointer 2 so as to be movable in any direction and to any extent within the limits of the pattern board. The movements of the pointer, which is supported by the usual carriage 3, are reduced to their 105 vertical and horizontal components through the horizontally movable frame 4 and the vertically movable frame 5. In the machine shown the frame 4 carries a rack 6 which engages and actuates a pinion 7, while the 110

frame 5 has connected therewith a vertical rack 8 which engages and shifts a pinion 9 (see Figs. 4 and 5). The pinion 7 is fixed on a shaft 10, which is supported in suitable bearings, and carries a gear 11 which 5 meshes with two pinions 12 and 13, secured respectively to sleeves 14 and 15, mounted with freedom for both longitudinal and rotary motion on the corresponding shafts 16 and 17. Toothed arms or dogs 18 and 19, 10 secured respectively to the sleeves 14 and 15, are adapted to be engaged, by longitudinal movement of the sleeves, with the toothed rims of the usual punch controlling drums 20 and 21, which are shown in this 15 instance as perforated. The sleeves 14 and 15 are shifted alternately so as to couple the drums 20 and 21 in alternation with the gears 13 and 12, in order that they may be shifted through the gear 11 in accordance 20 with the horizontal movements of the pointer 2, by arms 22, 23 of rods 24, 25 which are reciprocated in alternation by the grooved cams 26, 27, through rock shafts 26', 27'. 25

The pinion 9 is fixed on a sleeve 28 which carries a gear 29 in mesh with pinions 30, 31 on sleeves 32, 33 which are free to move longitudinally and to rotate on the shafts 30 16 and 17 respectively and are provided with toothed arms or dogs 34, 35 for engagement with the toothed rims of the punch selecting drums 36, 37. The sleeves 32, 33 are engaged 35 by arms 38, 39, of rods 40, 41 which are reciprocated in alternation by the grooved 40 cams 26, 27 as already described. In this manner the drums 36, 37 are coupled in alternation through the gear 29 to the pointer 2 in order that they may be shifted rotarily in accordance with the vertical movements of the pointer.

The punching devices proper, indicated generally at 42 in Figs. 3 and 5, may be constructed and arranged in any suitable manner. They are herein shown as constructed 45 and arranged as shown and fully described in Letters Patent of the United States No. 1,104,641, issued July 21, 1914. The punch controlling needles 43 for the horizontal movements and the punch controlling needles 44 for the vertical movements are shown as mounted for independent movement in a carrier 45 which receives its horizontal movements through a connecting rod 46 from an arm on the oscillating shaft 47 which is actuated by the grooved cam 48. The horizontally moving carrier 45 is itself supported in a vertically moving carrier 45^a which is actuated by an arm 45^b of an oscillating shaft 45^c which in turn is actuated by a grooved cam 45^d.

Between sets of needles 43, 44, which control the punches for the stitch movements of the fabric frame, there is located, in the vertically moving carrier 45^a, the selecting slide

49 which controls the punches for special functions. This slide is constructed and arranged and operates substantially as fully shown and described in Letters Patent of the United States No. 1,104,551, dated July 21, 1914, being shifted, in the present instance, through the rod 50, arm 50^a, shaft 50^b, and chain or belt drive 51, from the hand lever 52 under the control of the operator.

The punches 53, which are controlled by the slide 49, are offset in the carrier 45^a to the rear with respect to the punches 54 and with respect to the direction of movement of the card which is being punched, indicated 80 by the arrow in Fig. 6, the punches 53, as will be understood, being those which form the holes for controlling the special functions of the embroidering machine, while the punches 54 are those which form the 85 holes for the control of the stitch movements of the fabric frame. The reason for this construction of the machine will now be explained. If the pointer 2 is moved over the pattern board from *a* to *b*, as indicated 90 in Fig. 2, the punch selecting drums 21 and 37, for example, will be shifted, the one in correspondence with the horizontal component of that movement and the other in correspondence with the vertical movement. 95 If the pointer 2 is then moved from the point *b* to the point *c*, the drums 20 and 36 will then be shifted in like manner. The punching movement of the punches which have been selected by the drums 21 and 37 100 for the stitch *a*—*b*, takes place simultaneously with the shifting of the drums 20 and 36, since the machine is a two-cycle machine. If it is necessary, according to the pattern, to punch holes for a special function simultaneously with the punching of the holes for the stitch *b*—*c*, the hole or holes for such special function must be in the same line on the card with the holes for the stitch *b*—*c*. As however the operation of the slide 110 49 which selects the special function punches is not a two-cycle operation the punching of the hole or holes for the special function would take place immediately upon the shifting of the slide 49, and since, as already explained, the actual punching by punches selected by the drums follows the shifting of the drums by a period of time which corresponds with the space between two successive lines of holes in the card, the 115 special function hole or holes, if formed simultaneously with the shifting of the drums, would occur too early by a period of time represented by the space between successive lines of holes in the card. Therefore the 120 special function punches must be displaced to the rear, with respect to the stitch-controlling punches. Referring to Fig. 1 it will be seen that seven lines of holes are shown in the card. The holes of the series *x* repre- 125 130

sent the holes for the horizontal movements of the frame; the holes of the series *y* represent the holes for the special functions and the holes of the series *z* represent the holes for the vertical movements of the frame. It will be seen that if the punches 53 and 54 were not displaced relatively as described and shown, it would happen that at the same time when the holes for the stitch *a*—*b* are punched the drums for the stitch *b*—*c* would be shifted and the special holes which should be coördinated with the stitch *b*—*c* would be initiated by the operation of the lever 52 so that they would be coördinated with the punches for the stitch *a*—*b* and thereby, for example, if the stitch *a*—*b* corresponds to the line VI of the card, the holes for the stitch movement, in the series *x* and *z*, would be in row VI and the holes of the series *y* would also be in the row VI. The holes of the series *y* would therefore be punched too early as they should appear only in row VII in order to initiate the special function simultaneously with the stitch *b*—*c* of the frame which is initiated by the holes in the line following line VI, that is, in line VII. By reason, however, of the displacement of the punches 53 and 54 by the space between successive lines of holes the result follows that when the holes of the series *x* and *z* of the line VI, corresponding to the stitch *a*—*b*, are punched, the holes of the series *y*, produced at the same time with the holes for the stitch *a*—*b*, are punched, not in the line VI, but in the line VII. Therefore, when, by the following operation of the punching machine, the holes in the series *x* and in the series *z* for the stitch *b*—*c* are punched, they will be in the same line VII with the holes for the special function which, in the previous operation, had been punched in the row VII.

I claim as my invention:

1. In a machine for punching jacquard cards, the combination of a vertically moving carrier, a horizontally moving carrier mounted therein, stitch-controlling punches and special function punches carried by the vertically moving carrier, controlling needles for the stitch-controlling punches mounted in the horizontally movable carrier, selecting devices for coöperation with the needles and selecting means for coöperation with the special function punches.
2. In a machine for punching jacquard cards, the combination of a vertically moving carrier, a horizontally moving carrier mounted therein, stitch-controlling punches and special function punches carried by the vertically moving carrier, controlling needles for the stitch-controlling punches mounted

in the horizontally movable carrier, selecting devices for coöperation with the needles, and a selecting slide mounted in the vertically moving carrier for coöperation with the special function punches.

3. In a machine for punching jacquard cards, the combination of a horizontally moving carrier, punch selecting needles mounted therein, a punch selecting drum for coöperation with the needles having a toothed edge, a sleeve free to rotate and to move longitudinally on the same axis with the drum and having a toothed arm or dog for coöperation with the drum, means to rotate the sleeve and means to shift the sleeve longitudinally.

4. In a machine for punching jacquard cards, the combination of a horizontally moving carrier, punch controlling needles mounted therein, oppositely disposed punch selecting drums for coöperation with the needles each having a toothed edge, sleeves free to rotate and to move longitudinally and on the same axis with the drums respectively and having each a toothed arm for coöperation with the corresponding drum, pinions on said sleeves, a gear meshing with said pinions and means to shift said sleeves alternately into and out of engagement with the corresponding drums.

5. In a machine for punching jacquard cards, the combination of stitch-controlling punches, special function punches, selecting devices for the stitch-controlling punches, selecting devices for the special function punches and means for actuating all of the punches simultaneously, the special function punches being displaced one space to the rear with respect to the stitch-controlling punches.

6. In a machine for punching jacquard cards, the combination of stitch-controlling punches, special function punches, two-cycle selecting devices for the stitch-controlling punches, the two sets of selecting devices operating in alternation, selecting devices for the special function punches, and punch operating devices for all of the punches and operating the punches selected by one set of selecting devices during the movement of the other set of selecting devices and simultaneously operating the special function punches, the special function punches being displaced one step to the rear with respect to the stitch-controlling punches.

This specification signed and witnessed this 15th day of January A. D. 1914.
